UNITED STATES PATENT OFFICE.

NILS O. LINDSTROM, OF NUTLEY, NEW JERSEY, ASSIGNOR TO ALONZO B. SEE, OF NEW YORK, N. Y.

AUTOMATIC CIRCUIT-CONTROLLING SYSTEM FOR ELECTRIC ELEVATORS AND THE LIKE.

1,074,962.

Specification of Letters Patent.

Patented Oct. 7, 1913.

Application filed October 18, 1911. Serial No. 655,341.

To all whom it may concern:

Be it known that I, NILS O. LINDSTROM, a citizen of the United States, residing at Nutley, in the county of Essex and State of New Jersey, have invented certain new and useful Improvements in Automatic Circuit-Controlling Systems for Electric Elevators and the like, of which the following is a full, clear, and exact description.

10 This invention relates to electric elevator control systems and the like and has for one of its objects the provision of automatic means in a system of this character for varying the circuit conditions in accordance with 15 the direction of travel of the elevator car, the load thereupon, and the speed of travel of said car.

A further object of the herein described system is to facilitate and simplify the handling of an elevator car and to insure greater accuracy in stopping the car at determined points in its path of travel, especially when descending under heavy loads.

My novel system is intended to, and in 25 practice does, enable the operator to handle large motors with a more graduated automatic control than has been hitherto possible; and in fact, to eliminate, in very large measure, the personal equation or skill of 30 the operator. In this connection it may be noted that the present system practically prevents, under any circumstances, a large inrush or surge of current to the motor during the slowing down thereof as well as in 35 the speeding up.

These and other objects of my invention will be hereinafter described and more particularly pointed out in the claims appended hereto.

40 In the accompanying drawings which form a part hereof and in which like reference characters designate like parts throughout the several views: Figures 1 and 1^a are respectively the upper and lower 45 halves of a wiring diagram embodying the system to which this application relates. Fig. 2 is a simplified diagram of the line and dynamic-brake circuits.

50 Referring first to Fig. 1, adjacent the top is a positive binding post 2 and a negative post 3 by means of which current is supplied to the system.

Up and down magnets.—A circuit breaker 4-5, of any suitable construction serves,

when closed, to deliver the current from post 55 2 to a line wire 6, via the parts 4 of the switch or circuit breaker and a connection 7 leading thereto from pole 2. The current traverses wire 6 to a post at the bottom of the board designated S1, from whence it is 60 led by a connection 8 to a corresponding post s1 on the board of the motor. The circuit divides at s1, the bulk of the current passing through the series field 9 immediately adjacent the armature 10, and the 65 lesser portion traversing the shunt field coils 11 (11'), passing to said coils via post f1. The current through the series field 9 passes from terminal s2 to the series brake coils 12, via wire 13, and then flows 70 through wire 14 to terminal SB. From thence the series field current passes along wire 15 to post 16, where the circuit divides, one branch including the retarding or 75 overload magnet 17, post 18, and a connection 19 to the conductive arm 20' of the circuit breaking magnet or control 20 which cuts out the series turns or compounding effect in the manner hereinafter described. The remaining branch of this portion of the circuit, starting from post 16, consists of a 80 variable resistance 21 which extends directly to the arm 20' above referred to.

A connection 22 is provided between post 18 and a lead 23, and current flowing over 85 wire 22 is adapted to pass either through the armature 24' of a magnet 24 hereinafter referred to, or the similar armature 25' of a magnet 25, according to the positions of these parts. Armature 24' is adapted to be 90 swung over into electrical connection with a contact 26 when it is intended that the elevator car shall descend; while armature 25' similarly engages contact 27, when the car is to ascend; contacts 26 and 27 being 95 disposed at the respective extremities of the lead 23. Beneath the lead 23 is a lead 28, at the respective extremities of which are contacts 29 and 30, the former being adapted for engagement with the armature 31' of 100 a magnet 31 while the latter is adapted to engage the armature 32' of a magnet 32. The lead 28 normally delivers current to the negative side 5 of the circuit breaker from whence the current flows via a connection 33, corresponding to connection 7, to 105 the negative post 3 above referred to.

An inspection of the simplified wiring

diagram shown in Fig. 2 will serve to show the relationship of the partial line circuits already considered. Current is led in at 2 and passes thence wholly through the series brake 12, and series field 9, provided that the armature 20' is in open circuit position. When the coil or magnet 20 (shown in Fig. 1) which corresponds to this armature, is energized sufficiently, current will 10 be short circuited around these series field and brake coils, through armature 20'. In any case however the current flows through the wire 22 to lead 23, and according to whether the coils or magnets 24 and 32, or 15 25 and 31 are energized, said magnets being actuated in pairs, current will pass from 23 through 26 and 24' and from thence through a connection 33' to the several resistances, circuit breakers, etc., hereinafter 20 described, returning to lead 28 via a connection 34, corresponding to connection 33', and armature 32'; or from 23 via 27, armature 25', connection 34, etc., to 33' and armature 31'.

25 *Controlling circuits.*—Let us next consider the controlling or subsidiary circuits which actuate the up and down magnets 24, 25, 31, and 32 together with other devices. The lead 6 is tapped by a connection 35 which 30 delivers current to a lead 36 which extends between a pilot magnet 37 and an actuating magnet 38, both of which latter will be considered later more particularly. A branch lead 39 extends from 36 to a fuse 40, and the 35 latter is in turn connected via wire 41 with a pivoted contact arm 42. When this arm is disposed as shown in Fig. 1, the elevator car is at rest; but when the said arm is moved from the position marked, L so that it engages contact D, the mechanism will immediately and automatically set itself for the first or slowest speed down of the car, current passing from 42, through D to a lead 43 which is in circuit with the magnet 32. 40 45 From 32, the current flows along wire 44 to magnet 24 and from thence through a connection 45 to a binding post DR.

For the purpose of this specification, a direct connection 45' has been shown between 50 post DR and a second post UDR, but in practice this connection would include various devices in series which need not be herein referred to as they, *per se*, form no part of the present invention, a simple connection between DR and UDR sufficing when the system is controlled by means of the arm 42. Current leaves UDR via 46 and passes through a variable resistance VR, the purpose of which is to vary the strength of 55 the up and down magnets (24, 31, 25, 32). Assuming that the pilot solenoid core PS, hereinafter referred to, is in its downmost position, current will flow from VR through 47, contact 48, movable contact 49 which is 60 fixedly secured to and in electrical communica-

cation with a contact plate 50, to said plate, and from thence via connections 51, 52 to 3. If contacts 48 and 49 are not properly in engagement or if resistance is introduced at such portion of the circuit, current will flow 70 through VR to 53 and thence directly to 52 and 3. This purpose of the arrangement of branch circuits just described is to prevent the up and down magnets 24—31, etc., from acting when the core of solenoid PS above 75 referred to is not initially disposed in its lowest position, since current through 47 encounters considerably less resistance than does the current through 53. To resume, therefore, the setting of the arm 42 in its 80 D position, moves the armature 24' and 32' into their circuit closing position by the action of magnets 24 and 32 and current flows at first through both the series and shunt fields of the motor. In addition to this current is passing through both the series brake coil 12 and the shunt brake coil 54, since the series brake coil is, of course, in series with the series field, and current reaches the shunt brake coil via arm 24' which has been 85 drawn into engagement with contact 26, and through this arm to contact 55, lead 56, contact 57, wire 58, binding post BR, and lead 59. It passes out of the shunt winding 54 of the brake via lead 60, post BR', wire 61, 90 fixed contact 62, movable contact 63, and fixed contact 64, wires 65 and 66, contact 67, switch arm 32', which is in engagement with contact 67, contact 30, to lead 28, and out via side 5 of the circuit breaker. A governor 95 switch controlled coil or magnet 68 operates the movable contact 63, and as this coil is normally energized, receiving current through wires 69—70, which respectively lead to series field post S2 and the usual 100 elevator switch GS, current passing from GS via 71, the movable contact 63 is held in engagement with contact 62 and 64, completing the brake circuit just described. The 105 particular means employed for breaking this 110 circuit need not here be described as they form no part of the present invention.

115 *Slow speed resistances.*—When the controlling element, in this case the arm 42, is set for first or slowest speed down of the elevator car, current can pass via conductor 33' above referred to, through blow out 72, lead 73, to a hold-back coil 74, hereinafter referred to, through the latter to wire 75, and thence through the resistance disposed 120 between LR5 and R2. The current may emerge at R2 and traverse wires 76, 77 and 78, to the armature binding post a2 passing thence over conductor 79 to the armature of the motor and thereafter through 125 lead 80, post a1, wire 81 and wire 82 to R1. The current then traverses the line resistance between R1 and LR1, and passes on over wires 83 and 84, blow out 85, to wire 34, above referred to. Tracing this portion of 130

the circuit on the diagram shown in Fig. 2, current passes from 24' to 33', to 75 through the resistance 86, which corresponds to that between LR5 and R2 in Fig. 1, thence via connection 76, the motor armature, wire 80, resistance 87, which corresponds to that between R1 and LR1 above referred to, and out through 34, 32' and 28. As the speed in question is the lowest possible, the means for maintaining this slow speed should next be considered. Referring therefore back to the point R2 from which the line current was flowing to 76—77, it will be noted that this current divides at A2, a portion flowing to the armature in the manner described and a second portion flowing over the switch arm 38' of magnet 38, above referred to, to a contact 5SR, thence over wire 88, SR5, through a dynamic brake resistance, 89 to SR1, wire 90, blow out magnet 91, wire 92, contact 93, the lower end of a switch arm 94', and thence through 82, to R1, etc. If therefore the speed of the car tends to increase, more of the line current and also more of the counter E. M. F. current from the motor, which is being driven as a generator, will pass through the dynamic brake resistance 89, effectively checking the tendency to race.

Second speed resistance.—Considering now that the contact arm 42 has been moved to position D2, current then passes from said arm to contact D2, and from thence, for the purpose of setting forth briefly the particular invention to which this application relates, via connection 95 to post UD2. It will be seen that current may flow from this post up through wire 96, and also down through wire 97. Following that portion of the shunt going upward through 96, current will flow successively through the pilot solenoid PS, wires 98, 99, 100, contact 101, plate 102 (which is adapted to be carried by, but is insulated from contact 49 above referred to), contact 103, wire 104, contact 67 and out through 32'. Following the down flowing branch from UD2, current will pass over 97, and through the actuating magnet 94 of the switch arm 94', above referred to. This switch arm is normally in contact with the contact 93 above referred to, but its upper end is adapted to engage a contact 1LR when its magnet 94 is energized in the manner just described. Movement of switch arm 94' to contacting position with 1LR occurs therefore immediately the car controlling devices are set for second speed down. In fact this arm is the first to cut in upon establishing contacts for such speed, and the corresponding speed when ascending, and also the first to cut out upon dis-establishing such circuit conditions. It should here be stated that the circuit is constituted as described only so long as the core of the pilot solenoid has not moved upwardly to its

uppermost position. When this has occurred, contact between 102 and contacts 101 and 103 is interrupted and current flowing down through 98 is forced to pass through 98' a resistance 105, wire 106, contact 107 (which co-acts with switch-arm 31' when the latter is in circuit closing position), wire 108, contact 67, switch arm 32', and thence out as above described. This introduction of resistance 105 into the circuit occurring as it does, only after the core of the solenoid has reached the end of its upward movement, results in cutting down the flow of current through the solenoid at a time when a heavy flow of current is not needed therethrough, and the resistance 105 hence acts as a cooling resistance for the solenoid coil and also for the coil of magnet 94.

Line and dynamic brake resistance switches.—Let us next consider the effect of actuating switch arm 94'. Current had previously been flowing through 80, 81, 82 and the line resistance 87. Movement of arm 94' breaks contact at 93 and makes it as 1LR. As a result the line resistance 87 is in effect cut out of circuit, the bulk of the current flowing therearound via arm 94', lead 84, to blow out 85 and thence to conductor 34, etc. As the pilot solenoid has been energized as described, contact plate 50 which moves upwardly from plate 102, and is at all times insulated therefrom, first engages the yielding contact 109; and this completes the circuit which controls magnet 38 above referred to. Current will therefore flow downwardly through 36, as above described, through magnet 38, to wire 110; thence through wire 111 to contact 109, plate 50, and wires 51 and 52, to 3. As plate 50 continues to rise it successively engages contacts 113, 114 and 115; contact 113 controlling actuating magnet 116, current flowing from 36, through 116 and wire 117 to 113; contact 114 controlling magnet 118, current flowing from 36, through 118, 119', 119 to 114; and contact 115 controlling magnet 120, current being drawn from wire 36, passing from 120 via 121, through point 122, lead 123, to contact 115. The successive actuations of the magnet arms 38', 116', 118' and 120', by means of the corresponding magnets 38, 116, 118 and 120, effects a step by step or substantially gradual reduction of resistance in the armature circuit, since arm 38' contacts with 2LR; arm 116' with 3LR; arm 118' with 4LR; and arm 120' with contact 5LR; 2LR being in communication with a point LR2 in the line resistance via lead 124, 3LR with a second point LR3 in 125 said resistance via lead 125 and 4LR with a third point LR4 of the same via lead 126. Thus not only is the line of resistance 87 cut out in the manner already described, but successive parts of resistance 86 are one after 136

- another cut out, the arm 120' being the last operated and making contact with 5LR, from which a lead 127 extends directly to coil 74, above referred to, which is in electrical communication with the lead 75; substantially no line resistance being in circuit after the actuation of arm 120', except the series winding of the field and brake.
- 10 The conductive member 77 is, as has been stated, in communication with the armature binding post a2, via lead 78 and post A2, and when the several magnets 94, 38, 116, 118 and 120 are not energized, current flows through the lower portions of the arms corresponding to these magnets to a series of contacts respectively designated 93, 5SR, 4SR, 3SR and 2SR. Contact 93 is connected via wire 92, blowout coil 91 and lead 90 with the point SR1 of the dynamic brake resistance. Correspondingly contact 5SR communicates with point SR5 in this resistance by means of lead 88, previously referred to; 4SR with point SR4 of said resistance by lead 129; 3SR with SR3 via 130; and 2SR with SR2 via 131.
- 15 When the successive arms 94', 38', 116', etc., are being actuated in the manner just described, the first of these, to wit, 94', breaks at 93 the circuit which includes the entire dynamic brake resistance so that the successive actuations of arms 38', 116', 118' and 120' are, in this case, in so far as the dynamic brake is concerned, without effect; the dynamic brake having been entirely removed at the start, with the exception of such portion thereof as may be introduced by the action of the first automatic dynamic-brake switch, hereinafter referred to; and then only provided that there has been need for such braking action. In any case, however, since the rotation of switch arm 94' counter-clockwise breaks a circuit hereinafter described which controls the said first automatic switch, this possible residual braking action can only be momentary.
- 20 *Shunt field resistance.*—When arm 94' is moved into engagement with contact 1LR, current is delivered to a lead 132, from said contact, which lead extends to a magnet 133; lead 134, connecting said magnet to the wire 75, above referred to. The armature 133' of magnet 133 is adapted for engagement with a contact 135, and the pivoting stud thereof is connected via wire 136 with the post F3, which post is in turn connected with the binding post f3 of the motor by means of a lead 137. A corresponding post f4 is connected to a post F4 via lead 138, and this post receives current over wire 139 from the arm 140' of an electro-magnet 140, said arm being normally in engagement with a contact 141 which is in communication, via wire 142, with contact 135 above referred to. When therefore magnet 135 is energized in the manner described, switch-arm 138' closes the circuit which includes switch-arm 140' 70 and the shunt field connections leading from posts f3 and f4; and thus short circuits the outer and high resistance shunt field coils 11'. Switch-arms 133' and 140' are hence in series and jointly control this 75 part of the shunt field, and when one or the other of these switches is open, the current flowing through the shunt field from f1 will be forced to traverse not only the low resistance turns 11, but also the high 80 resistance turns 11', emerging via the post f2 in either case. Current leaving f2, it may here be noted, passes via 143' to post F2, and from thence over 144' and contact 30 to lead 28.
- 85 *Means for cutting out the compounding effect.*—Between magnets 133 and 140 is the magnet 20 above referred to, the contact making arm 20' of which is adapted for engagement with contact 143 which is directly connected to lead 6. Hence when magnet 20 is energized the series turns are cut out, current short circuiting across directly from lead 6 to lead 22 via contact 143, arm 20' and wire 19. Let us next consider the action of this magnet 20. It cannot be energized until contact has been effected between 114 and plate 50, since it draws current from connection 19, the current passing from magnet 20 via wires 144, 119, 114, 50, etc. Again magnet 20, is opposed by the pull-lock magnet 74, which latter is not shorted until the magnet 120 has been energized. The tendency of magnet 20 to act, therefore, is variable, and depends upon the counter-electromotive force of the motor; while the tendency of magnet 74 to act is also variable and depends on the amount of line current flowing. Assuming now that the car is ascending or descending and that it has attained a high speed resulting in a drop in current through the line, then retarding magnet 74 will not be sufficiently strong to oppose the action of magnet 20 and the switch-arm 20' will move to its closed position ahead of arm 120', instead of after movement of the latter, as would ordinarily be the case, thereby preventing possible reversal of current in the line which would oppose the shunt field current and weaken the field; which latter action might result in the car running away. In other words, when line current is low there is no need of any compounding effect and this arrangement results in cutting out the series field when the line current is low or before it is reversed, due to counter E. M. F. of the motor.
- 90 *Third speed down.*—Assuming now that the arm 42 be swung farther to the right 95
- 95
- 100
- 105
- 110
- 115
- 120
- 125
- 130

into contact with D3, which corresponds with the third speed down of the car. Current passes from 42 to D3 and (again merely for the purpose of simplifying the present disclosure) over connection 145 to post UD3, and from thence over 146 to magnet 140, energizing the same and causing arm 140' to break contact with 141. The current leaves magnet 140 via 147 which delivers into 123, uniting with current passing over 123 from magnet 120. As stated, the energization of magnet 140 pulls arm 140' out of contact with 141, thereby interrupting the short circuit about the high resistance outside turns 11' of the shunt field and thereby lowering the total amount of current which passes through the shunt field. To review briefly, therefore, the action of magnets 133 and 140: When the machine is at rest, the switch-arm 133' is in open position and the high resistance turns are effectively in circuit with the shunt field, the field accordingly being weak. When the switch-arm 133' is moved to its closed position, immediately contact is effected between arm 42 and D, these high resistance turns are cut out and the field correspondingly strengthened. When the arm 42 is moved to the highest speed position D3, switch-arm 133' remains in closed position, but switch-arm 140' opens and the field is again weakened to permit of an acceleration of speed of the motor; arm 133' remaining closed until the motor stops, which results in a strong field being present at stopping, an especially valuable feature when descending with a heavy load, since the brake need not be wholly depended upon. The action of the hold back coils 17 and 74 is of importance in this connection. The latter coil is adapted to hold back the switch-arm 20' in case the line current is excessive, due to a heavy load on the motor, until the magnet 94 has acted. The hold back coil 17 similarly opposes the magnet 140 and holds the arm 140' in its circuit closing position until the line current falls a certain amount depending on the load. In other words, if a heavy load is upon the motor, arm 20' is held back until arm 94' has acted; then the closure of switch-arm 20' permits some current which would otherwise have passed through magnet 17 to pass therearound, weakening it, and as the car has started to increase its speed, and as correspondingly the line current has fallen to a determined amount, magnet 17 is so much weakened that it cannot successfully oppose magnet 140 longer, and arm 140' then swings into its closed position. This action of switch-arm 140' can only occur, normally, when the operator is holding arm 42 at high speed position (in either direction) since otherwise magnet 140 is not energized. The variable

resistance 21 is provided for the purpose of adjusting the strength of magnet 17 to suit conditions.

Speed reducing and stopping actions.—Considering next the circuits established for the several speeds of the car when the arm 42 is withdrawn successively from D4, D2 and D. Upon swinging arm 42 away from D3 toward position L, the circuit which energizes magnet 140 in the manner above described is, of course, broken, and arm 140' moves back into engagement with contact 141, reestablishing the short circuit about the high resistance shunt field turns 11', and the speed of the elevator car is accordingly diminished. When 42 is moved from D2 toward L, the first result is the deenergization of magnet 94 with consequent movement of its arm 94' into the position shown in Fig. 1, by reason of the interruption of the circuit 42, D2, 95, UD2, 97, 94, etc., previously traced, and resulting in reestablishing the dynamic brake. Simultaneously the pilot coil or solenoid PS is also deenergized since it draws current from UD2 via 96. The contact plate 50 accordingly descends at moderate speed, being provided with a dash-pot 148, and the several circuits controlling arms 120', 118', 116', and 38' are interrupted in the order named, owing to the successive separation of plate 50 from contacts 115, 114, 113 and 109. It will be seen, therefore, that while arm 94' takes precedence in movement over arms 38', 116', 118' and 120' when contact is made with D2, it also takes precedence over these arms when contact at D2 is interrupted. As arm 94' cuts line resistance 87 in or out and correspondingly dominates the dynamic brake circuit as a whole, it is evident that the several resistances controlled by magnets 120, 118, 116 and 38 will be re-introduced into the dynamic-brake circuit successively when this circuit has been rendered operative by the movement of the switch-arm 94'. In other words the dynamic-brake is applied gradually when the car is being brought to slow speed or rest and the operator need not be depended upon. I therefore am enabled to automatically cut out the dynamic brake effect substantially immediately upon starting up from slow speed and to gradually reestablish it upon slowing down or stopping. Finally when arm 42 is returned to L, thereby breaking the circuit which dominates magnets 24 and 32; the arms 24' and 32' move to open circuit position, current to the motor is shut off and the brakes are applied, as current ceases to flow through the brake coils.

Operation during ascent.—In order to cause the car to ascend, arm 42 is first moved to U, and establishes the following circuit: 4, 6, 35, 36, 39, 40, 41, 42, U, 150, magnet 31, 151, magnet 25, 152, UR, 153 (for pur-

poses of this application) to the common return binding post UDR above referred to, current flowing thence precisely as did current from DR. When current is passed through the above circuit, magnets 25 and 31 are energized and actuate arms 25' and 31', closing the primary circuit and allowing current to flow via 6, S1, through the armature, series field and series brake coils in the manner previously described, thence through SB, 15, 17, 22, 23, 27, 25', 34, 85, 84, 83, line resistance 87, wires 82, 81, post a1, the armature, a2, 78, 77, 76, R2, line resistance 86, 75, 74, 73, 72, 33', 31', 29, 28, 5; thus passing current through the motor armature in a direction opposite to that previously described. Upon moving arm 42 to its second-speed-up position, i. e. into contact with U2, current will flow from 42 to U2, and (for purposes of this application) via 154 to UD2, at which point it divides precisely as in the preceding case, current flowing down over 97 and actuating switch-arm 94', and current flowing up over 96 and energizing the pilot solenoid PS with similar results. Upon moving 42 to U3, current may pass over 155, from U3, to the common return binding post UD3, whence it flows over 146, 140, etc., precisely as in the case of current delivered from D3 via 145, (previously discussed) and with similar effects.

Automatic dynamic brake switches.— Considering now more especially the function of the automatic dynamic brake switches elsewhere referred to. Current for both of these is drawn from contact 4LR, and passes over wire 160, contacts 161, which are controlled by magnet 37, wires 162, 163, automatic magnet 164, wire 165, to contact 93; and it is hence evident that the switch-arm 164' of magnet 164, can only be actuated when switch-arm 94' is disposed, as shown in Fig. 1. The automatic switch circuit branches at 166, so that current also passes through the second automatic switch magnet 167, flowing thence via 168 to 93; the switch-arm 167' of magnet 167 hence also being dominated by switch-arm 94'. Magnet 164 is preferably set to operate at a lower potential than magnet 167, and the former will therefore operate first.

When the pilot magnet 37 lifts, breaking circuit at 161, current to magnets 164 and 167 will be taken solely from R2, via 76—169, resistance 170, and wire 171, instead of from R2 and 4LR, giving practically the exact counter E. M. F. from the motor through said resistance 170. At slow speed, therefore, magnets 164 and 167 receive current from the line together with the counter E. M. F. available, while upon slowing down from high speeds current for said magnets is drawn solely from the armature. This results in a saving of current and also

enables the use of the same strength magnets at 164, 167, as at 116, 120, etc., resulting in uniformity.

When magnet 164 acts the following dynamic-brake circuit is established: Current flows from the armature at a1 through 81, 82, R1, resistance 172, post SR6, 173, to automatic switch-arm 164', thence via contact 7SR, blowout 174, leads 175, 76, 77, 78 to a2. Correspondingly when magnet 167 acts it short circuits a part of the permanent dynamic-brake resistance and the current through the dynamic-brake circuit flows as follows: a1, via 81, 94', 93, 92, 91, 90, SR1, resistance 176, SR8, 177, 8SR, 167', line wire 178, SR9, resistance 179, SR4, 129, 4SR, and, in case switch 116' is in its back position as shown in Fig. 1, current will flow thereover to 77, 78 and back to a2. If switch 116' is forward then the current flows on from SR4 through resistance 180, to SR3, 130, 3SR, and up switch 118' to 77, etc. If switch 118' be also in its forward position further resistance may be included in like manner until a switch is found in its back position or if none be so disposed, the current will flow through all of the dynamic brake resistance to R2 and thence out via 76, 77, etc.

For convenience in tracing circuits switch contacts 2SR, 3SR, 4SR, are respectively connected in the manner above described to points along the dynamic brake resistance which have been correspondingly designated SR2, SR3 and SR4. Contact 5SR similarly is electrically connected to SR5 via 88, current being received through resistance 179, which lies between posts SR5 and 10SR, the latter being connected by a lead 180 with a post SR10 in the upper line of resistance.

An inspection of the simplified diagram shown in Fig. 2 will render more clear the relationship of the several resistances and their controlling switches.

The automatic switches 164' and 167' cannot act after switch 94' has been actuated, for reasons previously given; while switch 164' normally closes before switch 167'. Switch 164' when closed affords a second path for the current through the dynamic brake circuit, said path comprising resistance 172, via 173, switch 164' and wire 175. When subsequently switch 167' closes, the resistance between SR8 and SR9 is short circuited. In general therefore, in descending, if the load be exceedingly heavy and the counter E. M. F. developed by the motor, as a result, be high, the automatic switches 164' and 167' successively increase the dynamic brake action by successively decreasing resistance in the dynamic brake circuit, or, briefly, these automatic switches put in an automatically variable dynamic brake across the armature, depending on the load.

Action of pilot magnet.—When the plate 50 has been moved into contact with 109, current flows from wire 36 through the pilot magnet 37, wire 181, a resistance 182, wires 183, 5 and 111 to contact 109 and thence out. If after the magnet 37 has been energized contact between 109 and 50 be broken, the magnet will still continue to be energized, since current will flow via 181 and a second resistance 184, 106, to 107; or to 67 via 107, 108, 10 66, according to the direction of motion of the car. The resistance 184 is much greater than resistance 182 and the current which flows through the circuit after 50 has been 15 separated from 109 is only sufficiently strong to hold the armature of magnet 37 in place after it has previously been lifted into its upper position by the stronger current. Now, when the machine gets up to substantially 20 its highest speed this pilot magnet 37, lifts and breaks the short-circuit around the resistance 170 in the automatic magnet control circuits, interrupting the flow of current to magnets 164—167 from 4LR. The 25 automatic switches 164'—167' are, under these conditions, dominated solely by the counter E. M. F. from the armature, when subsequently slowing down. In other words, 30 these automatic switches never act at high speed, but are jointly controlled by the counter E. M. F. from the armature and by line current when the elevator is speeding up, until substantially maximum speed is attained, and by the counter E. M. F. solely 35 when slowing down, if the latter be of sufficient strength.

Resumé.—It will be observed that my system comprises a plurality of automatically actuated elements and circuits which co-act 40 to meet the varying conditions of load and speed, encountered in practice, whether the car be ascending or descending; surging of heavy currents in the motor being prevented; while a dynamic brake is automatically 45 applied when required and in just the proper amounts. As a result, the car of an elevator operated in accordance with the principles of my invention is subject to a degree of control, especially when operating under 50 very heavy loads, which has not hitherto been attainable.

I am aware that it is possible to effect various modifications in my novel system without departing from the spirit of my invention and I hence desire to be limited 55 only by the scope of the claims appended hereto.

Having described my invention, I claim:

1. An electric control system comprising 60 a motor, means to supply current thereto, connections with said motor constituting a dynamic brake circuit, means for substantially immediately removing the dynamic brake as a whole, and automatic means for gradually applying said dynamic brake

while said motor is still adapted to receive current.

2. An electric control system comprising a motor, means to supply current thereto, connections with said motor constituting a dynamic brake circuit, said connections including a plurality of resistances, means for substantially immediately removing the dynamic brake as a whole after starting, and automatic means for gradually applying said dynamic brake while said motor is still adapted to receive current, said automatic means including switches adapted to cut said resistances successively out of said circuit.

3. An electric elevator control system comprising a motor, connections with said motor constituting a dynamic brake circuit, automatic means for substantially immediately removing the dynamic brake as a whole, a line resistance in circuit with said motor, said means also being adapted to cut out said line resistance from said motor circuit and automatic means for gradually applying said dynamic brake when slowing down.

4. An electric elevator control system comprising a motor, connections with said motor constituting a dynamic brake circuit, means for substantially immediately removing the dynamic brake as a whole, an electro-magnetic appliance and connections thereto for controlling said dynamic brake removing means, a line resistance in circuit with said motor, said means also being adapted to cut out said line resistance from said motor circuit, and automatic means for gradually applying said dynamic brake when slowing down.

5. An electric elevator control system comprising a motor, connections with said motor constituting a dynamic brake circuit, means for substantially immediately removing the dynamic brake as a whole, an electro-magnetic appliance and connections thereto for controlling said dynamic brake removing means, a line resistance in circuit with said motor, said means also being adapted to cut out said line resistance from said motor circuit, automatic means for gradually applying said dynamic brake when slowing down, and means co-acting with said automatic means for gradually introducing line resistance when slowing down.

6. An electric elevator control system comprising a motor, connections with said motor constituting a dynamic brake circuit and a line circuit, said dynamic brake circuit including a plurality of partial circuits with a determined resistance in each partial circuit, contact making and breaking means in some of said partial circuits, automatic devices for actuating said contact making and breaking means successively, circuit

making and breaking means for controlling substantially the entire dynamic brake circuit, and means for energizing said automatic devices after the circuit making and breaking means for the entire dynamic circuit has been actuated.

7. An electric elevator control system comprising a motor, connections with said motor constituting a dynamic brake circuit and a line circuit, each of said circuits including a plurality of partial circuits with a determined resistance in each partial circuit, contact making and breaking means in some of said partial circuits, automatic devices for actuating said contact making and breaking means successively in both the dynamic brake partial circuits and the line partial circuits, circuit making and breaking means for controlling substantially the entire dynamic brake circuit, and means for energizing said automatic devices after the circuit making and breaking means for the entire dynamic circuit has been actuated.

8. An electric elevator control system comprising a motor, connections with said motor constituting a dynamic brake circuit and a line circuit, said dynamic brake circuit including a plurality of partial circuits with a determined resistance in each partial circuit, contact making and breaking means in some of said partial circuits, automatic devices for actuating said contact making and breaking means successively, circuit making and breaking means for controlling substantially the entire dynamic brake circuit, means for actuating said last mentioned means, and co-acting means for energizing said automatic devices after the circuit making and breaking means for the entire dynamic circuit has been actuated.

9. An electric elevator control system comprising a motor, connections with said motor constituting a dynamic brake circuit and a line circuit, means for cutting resistance into and out of said dynamic brake circuit, said means including an automatic switch and an electromagnetic appliance for operating the same, said appliance normally receiving the current from the line circuit, and an automatic controlling switch for said automatic switch.

10. An electric elevator control system comprising a motor, connections with said motor constituting a dynamic brake circuit and a line circuit, means for cutting resistance into and out of said dynamic brake circuit, said means including an automatic switch provided with an electro-magnetic appliance for operating the same, said appliance normally receiving current from both the line circuit and the dynamic brake circuit.

11. An electric elevator control system comprising a motor, connections with said motor constituting a dynamic brake circuit

and a line circuit, means for cutting resistance into and out of said dynamic brake circuit, said means including an automatic switch provided with an electro-magnetic appliance for operating the same, said appliance normally receiving current from the dynamic brake circuit, at least.

12. An elevator control system comprising a motor, connections with said motor constituting a dynamic brake circuit and a line circuit, means for cutting resistance into and out of said dynamic brake circuit, said means including an automatic switch and an electro-magnetic appliance for operating the same, said appliance normally receiving current from both the line circuit and the dynamic brake circuit, and automatic means for stopping the flow of line current through said appliance when the motor is under a heavy load.

13. An elevator control system comprising a motor, connections with said motor constituting a dynamic brake circuit and a line circuit, means for successively cutting resistance into and out of said dynamic brake circuit, said means including a pilot apparatus provided with time element means for retarding the action thereof, said auxiliary means including automatic switches provided with electro-magnetic appliances for operating the same, one of said appliances adapted to respond to current of one strength and another of said appliances adapted to respond to current of a greater strength.

14. An elevator control system comprising a motor, a conductive line leading thereto, a plurality of auxiliary switches in electrical connection with said line, line resistances dominated by said switches, dynamic brake resistance also dominated by said switches, a master switch controlling substantially all of said dynamic brake resistance, and means for actuating said master switch before said auxiliary switches.

15. An elevator control system comprising a motor having a series and shunt winding, said shunt winding including both low resistance turns and high resistance turns, means for short circuiting said high resistance turns, said means including a switch, an electro-magnetic device for controlling said switch, and an electrically operated hold-back device adapted to oppose the action of said first mentioned device, said hold-back device being in circuit with said motor.

16. In an electric elevator control system, a motor, having a line circuit and a dynamic brake circuit, automatic means for varying said circuits in accordance with speed conditions, said means comprising a plurality of electro-magnetically operated controlling circuits for said switches, and a pilot device for successively varying said

controlling circuits, said pilot device comprising a plurality of contacts and electrically operated means for successively engaging said contacts, said last mentioned means being initially actuatable only by a current of determined strength.

17. In an electric elevator control system, a motor having a line circuit and a dynamic brake circuit, automatic means for varying 10 said circuits in accordance with speed conditions, said means comprising a plurality of electro-magnetically operated switches, a pilot device for successively varying said controlling circuits, said pilot device comprising a plurality of contacts and electrically operated means for successively engaging said contacts, said last mentioned means being initially actuatable only by a current of determined strength, a branched 20 controlling circuit for said device, and means for varying the flow of current through the branches of said circuit after said device has been actuated.

18. In an electric elevator control system, 25 a motor having series and shunt field windings, connections with said motor constituting a line circuit and a dynamic brake circuit, means for cutting out the series winding when the line current is low, said means 30 including a controlling circuit which includes an electro-magnetic device, said circuit normally drawing current from said dynamic brake circuit, and an electro-magnetic pull-back device adapted to co-act with said 35 first mentioned device to vary the action thereof, said pull-back device being normally energized by current passing through said line circuit.

19. In an electric elevator control system, 40 a motor having series and shunt field windings, connections with said motor constituting a line circuit and a dynamic brake circuit, a switch for cutting out the series winding, a resistance in said line circuit, 45 and means for cutting said resistance out of said circuit, said means adapted for actuation only after actuation of said switch when the line current is low.

20. In an electric elevator control system, 50 a motor having series and shunt field windings, connections with said motor constituting a line circuit and a dynamic brake circuit, a switch for cutting out the series winding of said motor, an electro-magnetic 55 device for actuating said switch, said device connected in said dynamic brake circuit, and a second electro-magnetic device adapted to oppose action of the device first mentioned, said second device connected in 60 said line circuit.

21. A multiple speed electric elevator control system comprising a motor having series and shunt windings, the latter comprising low resistance and high resistance turns, 65 automatic means for cutting out said high

resistance turns when the system is set for low speed, and separate automatic means for cutting in said high resistance turns when the motor is to be driven at a higher speed.

22. An electric elevator control system, comprising a motor having series and shunt windings, the latter comprising low resistance and high resistance turns, means for cutting said high resistance turns automatically into or out of circuit, said means comprising a switch which is normally closed when the motor is at rest, a control circuit including an electro-magnetic device for opening said switch, said circuit being normally energized when the motor is driven at a determined speed, and means for opposing the action of said device, said means including an electro-magnetic device in circuit with the armature of said motor. 80

23. An electric elevator control system comprising a motor, connections thereto constituting a line circuit and a dynamic brake circuit, said motor having series and shunt windings, the latter comprising low resistance turns and a supplemental resistance adapted to be connected in series therewith, a switch for cutting out said series winding, and means for automatically cutting said supplemental resistance out of circuit, said means being dependent in part at least upon the position of the switch aforesaid. 95

24. An electric elevator control system comprising a motor having connections thereto constituting a line circuit and a dynamic brake circuit, automatic electrically operated mechanism for varying said dynamic brake circuit, said mechanism including a plurality of electro-magnetic devices, circuits for controlling said devices and means including an electro-magnetic pilot device for varying current conditions in said circuits, said device having a part thereof displaceable by current of a determined strength, said part being adapted to be held in its displaced position by current of a lower strength. 100

25. An electric control system comprising a motor, a source of current supply therefor, means adapted to provide a plurality of speeds for said motor, a dynamic brake circuit connected therewith, and means adapted to throw the dynamic brake into circuit with said motor upon the provision of a given speed thereto and while current is being supplied to said motor. 115

26. A motor control system comprising a motor, a source of current supply, means adapted to control the supply of current to said motor comprising a plurality of electromagnets adapted to actuate switches serving as contact makers with the main line, said switches permitting current to pass through one or more banks of line resistances and through the field of said motor. 125

and means adapted to provide a dynamic brake in connection with the armature of said motor comprising a dynamic brake circuit including therein one or more banks of resistances and a switch-arm, said switch-arm being adapted to be thrown into and out of said dynamic brake circuit and to thereby connect and disconnect said dynamic brake circuit from said armature 10 upon the assumption of a given speed by said motor.

27. A motor control system comprising a motor, a source of current supply, means adapted to control the supply of current to 15 said motor comprising a plurality of electromagnets adapted to actuate switches serving as contact makers with the main line, said switches permitting current to pass through one or more banks of line resistance and 20 through the field of said motor, means adapted to provide a dynamic brake in connection with the armature of said motor comprising a dynamic brake circuit including therein one or more banks of resistance 25 and a switch-arm, said switch-arm being

adapted to be thrown into and out of said dynamic brake circuit and to thereby connect and disconnect said dynamic brake circuit from said armature upon the assumption of a given speed by said motor, and an 30 automatic dynamic brake adapted to be thrown in upon an excessive rise of counter E. M. F. developed by the motor.

28. A motor control system comprising a motor, a source of current supply therefor, a 35 circuit leading to said motor from said source of current supply, banks of resistance in said circuit, a dynamic brake circuit upon the brushes of said motor, banks of resistance in said dynamic brake circuit, contact 40 members in both of said banks of resistance, and unitary switch members having elements adapted to contact with contacts associated with both of said banks of resistance.

In witness whereof, I subscribe my signature, in the presence of two witnesses. 45
